SAFETY HELMET

Suzanne E. Vanderbilt, Royal Oak, Mich., assignor to
American Safety Equipment Corporation of Michigan,
Southfield, Mich.

Filed Mar. 20, 1968, Ser. No. 11,044

Term of patent 14 years

(Cl. D2—231)

FIG. 1

FIG. 2

FIG. 3

FIG. 4

FIG. 5

FIG.6

FIG.7

FIG.8

FIG.9

FIG.10

FIG.11

FIG. 1 is a top plan view of a safety helmet, showing my new design;

FIG. 2 is a front, elevational view thereof;

FIG. 3 is a left side, elevational view thereof, the right side being an identical mirror image;

FIG. 4 is a rear, elevational view thereof; and

FIG. 5 is a perspective view thereof, showing the front and left side.

FIG. 6 is a front elevational view of a second embodiment of the design shown in FIG. 1 wherein the band is extended down to the brim and the cut out is omitted;

FIG. 7 is a left side elevational view thereof, the right side being a mirror image;

FIG. 8 is a rear elevational view thereof; and

FIG. 9 is a front perspective view.

FIG. 10 is a front perspective view of a third embodiment of the design shown in FIG. 1 wherein the cut out on the band is omitted; and

FIG. 11 is a left side elevational view thereof, the right side being a mirror image thereof, top, front and rear views being substantially identical to FIGS. 1, 2 and 4 respectively.

I claim:

The ornamental design for a safety helmet, as shown and described.
